SHOWER DOOR ASSEMBLY

Ralph J. Dietrich, Los Angeles, Calif.

Application October 18, 1954, Serial No. 462,659

4 Claims. (Cl. 4—145)

This invention relates generally to improved bathing stall enclosures of the type comprising either or both movable and stationary panels, and more particularly has to do with improved panel assemblies facilitating ready access from shower stall interior to bathing equipment supported on the outer or dry side of such assemblies, the invention having desirable application to bathing stall door assemblies.

With regard to conventional shower stall construction in which, for example, an ordinary door separates the wet interior of the stall from the dry exterior, the wet bather is considerably inconvenienced in having to open the door and reach or step outward to obtain a drying towel or other equipment, which must be kept dry. In so doing, there is presented the danger of slipping on the wet floor of the shower stall or on the floor exterior to the stall, which also becomes wet as water drips from the bather. To my knowledge, no way has been found to eliminate these inconveniences, other than storing the drying towel somewhere within the shower stall interior, wherein the risk is created that the towel will become at least dampened, no matter how well stored during the showering process.

My proposed shower stall door assembly has distinct advantages over conventional and prior doors of this type in that means are now provided enabling the bather to gain ready access to dry bathing equipment without having to open the door and risk a fall by stepping or reaching out of the stall. Furthermore, the door assembly is such as to maintain the bathing equipment in a thoroughly dry condition, since communication between the interior of the stall and the support for the bathing equipment may be completely cut off during showering. In addition, the support is so located as to be readily accessible from the exterior of the shower stall, facilitating replacement of the equipment without having to open the door.

In keeping with the above described advantages, there is provided in the upper portion of the shower stall door a through opening communicating between the inner and outer sides of the door. A closure for the opening is hinged to open toward the inner side of the door, and the closure is preferably offset from the door so that a support for bathing equipment may be contained within the door assembly. To keep the support dry, the closure is normally retained in closed or covering relation with the opening at the shower stall side thereof, so that the support is readily accessible from the shower stall exterior. Access to the support from the interior of the shower stall is gained by swinging the closure away from the opening and into the stall interior.

All the various features and objects of the invention, as well as the details of an illustrative embodiment, will appear more fully understood from the following description of the accompanying drawings, in which:

Fig. 1 is a view of the outside of the shower door assembly;

Fig. 2 is a partly cutaway view of the rear of the shower door assembly facing the interior of a shower stall;

2

Fig. 3 is a sectional view of a portion of the door taken on line 3—3 of Fig. 1;

Fig. 4 is another section taken through the door on line 4—4 of Fig. 1; and

Fig. 5 is an enlarged sectional view of a small portion of the door taken on line 5—5 of Fig. 3.

As will appear from the drawings, the shower door assembly 10 is mounted within a rectangular opening 11 provided by shower stall entrance framework 12, which is affixed to the tiled wall 13. The door assembly 10 is pivotally mounted to the outer framework 12 by means of a vertical piano hinge 14 having one arm connected to the edge of the door frame 15 and the other arm joined to the leg of a right angle door jamb 16 mounted against the outer framework 12, as shown in Fig. 4. Another door jamb 16 is provided on the opposite side of the door on framework 12, so that the projecting legs of the jambs limit closing of the door as it swings toward the interior of the shower stall, in the usual manner.

Door frame 15, which defines the perimeter of the door assembly, is shown to comprise a U-shaped or channeled member opening toward the center of the door assembly. Extending horizontally between and joined to the vertically extending sections of the frame is another frame member of support 17, which may be conveniently formed to have an H-shape in section for the purposes to be described. That portion of the door assembly beneath support 17 may be constructed in the usual manner to include, for example, an opaque glass panel 18, the edges of which are enveloped by rubber channels 19 and 191, which preferably comprise neoprene or other synthetic rubber material. The rubber channels 19 and 191 may be pressure-set within the channels in support 17 and frame 15 to form a water-tight seal therewith.

That portion of the shower door assembly above the support 17 includes the novel construction which will now be described. The door frame 15 above the support 17 and the support itself generally define an opening 20 through the door, also bounded by a horizontal shelf 21 at the base of the opening and vertical side panels 22 at the sides of the opening. A closure 23 is carried at the rear of the through opening, offset from the plane of the door frame 15 toward the interior of the shower stall, and it forms along with the side panels and the shelf a type of open-front cabinet which is recessed toward the closure and toward the interior of the shower stall. The tops of the closure 23 and door frame 15 are spaced considerably below the top of entrance framework 12 to provide a steam exit therebetween.

The shelf is shown to include a downward projection 24, contained in rubber channel 25, which is pressure-set within an upwardly facing channel in support 17. The shelf 21 also includes front and rear uprights 26, the latter being joined to vertical door jambs 27 formed on opposite side panels 22. Vertical flanges 28 carried by the panels and projecting at right angles thereto are pressure-set in rubber channels 29 carried within opposite side frame members 15.

The closure 23 is shown to comprise a rectangular frame 30 supporting a rectangular pane of glass 31, the edges of which are enveloped by a rubber channel 32. The latter is pressure-set within the channeled frame 30 to form a water-tight seal therewith. Swinging movement of the closure 23 toward the interior of the shower stall is facilitated by a hinge 33, one arm of which is joined to a vertical side portion of the frame 30 and the other arm of which is connected to an extension 34 of the side panel 22. It goes without saying that the hinge 33 is positioned in such a way as to allow the closure to swing into position against the jambs 27 whenever closing of the through opening 20 is desired.

In conformance with the invention, a horizontal towel

bar 35 is supported between opposite side panels 22 in the position shown in Fig. 3, and towels 36 may be conveniently suspended from the bar as shown in Fig. 1. In addition, other bathing equipment may be carried by the shelf 21 beneath the bar. Since the closure 23 is positioned between the interior of the shower stall and the towel bar and shelf, water from the interior of the stall cannot wet the towels or other bathing equipment on the shelf when the closure is closed. When the bather desires to dry himself, he need only swing the closure inwardly toward the stall so as to gain ready access to the towels 36, instead of having to open the shower door itself and step out of the stall. Access to the towel bar from the exterior of the stall may be had at all times, as shown in Fig. 1 to facilitate replacement of the towels without having to open the closure or the door assembly. It is contemplated that the towel bar 35 may alternatively be carried by the closure at the outside thereof, so that when the closure is swung toward the interior of the stall, the towels will also be carried inward for ready use.

While the door assembly 10 has been shown and described as pivotally connected to the outer framework 12, it may be desirable to mount the door panel for sliding movement behind a stationary shower stall panel, in which case the frame structure for the opening should not project beyond the plane of the door on the outside thereof. It is also within the contemplation of the invention to operatively combine the closure and frame structure with an opening in a stationary shower stall panel rather than the door.

I claim:

1. In combination with a bathing stall shower structure comprising walls enclosing a stall compartment and water shower means within the compartment, an improved movable door assembly comprising an upright bathing stall main door for forming a portion of said walls and the stall enclosure and having an opening in the upper portion thereof through which unobstructed access may be had from the inside of the door to its outside, a movable closure for said opening directly accessible at the inside of the door for movement inwardly of the stall by an occupant thereof, and a towel support carried by said main door at the outside of said closure and extending substantially horizontally and parallel to the plane of said door for carrying a towel so that the towel is always accessible from the inside of the door through said opening when said closure is opened and at the outside of said door while remaining in the same position relative to the door.

2. In combination with a bathing stall shower structure comprising walls enclosing a stall compartment and

water shower means within the compartment, an improved movable door assembly comprising an upright bathing stall main door for forming a portion of said walls and the stall enclosure and including a frame forming an opening in the upper portion of the door through which unobstructed access may be had from the inside of the door to its outside when the door remains closed, a movable closure for said opening hinged to said frame and directly accessible at the inside of the door for swinging movement inwardly of the stall by an occupant thereof, and a towel support bar carried by said frame at the outside of said closure and extending substantially horizontally and parallel to the plane of said door for carrying a towel so that the towel is always accessible from the inside of the door through said opening when said closure is opened and at the outside of said door while remaining in the same position relative to the door.

3. In combination with a bathing stall shower structure comprising walls enclosing a stall compartment and water shower means within the compartment, an improved movable door assembly comprising an upright bathing stall main door for forming a portion of said walls and the stall enclosure and including a frame forming a rectangular opening in the upper portion of the door through which unobstructed access may be had from the inside of the door to its outside when the door remains closed, said frame including opposite sides projecting away from and at the inside of the door plane, a movable closure hinged to one of said frame sides in inwardly offset relation to said door plane and directly accessible at the inside of the door for movement inwardly of the stall by an occupant thereof, and a towel support bar carried by said frame sides at the outside of said closure and extending across said opening substantially horizontally and parallel to the plane of said door for carrying a towel so that the towel is always accessible from the inside of the door through said opening when said closure is opened and at the outside of said door while remaining in the same position relative to the door.

4. The invention as defined in claim 3 in which said frame includes an upper cross-member connecting said sides, said member extending substantially parallel to said bar and spaced a substantial distance thereabove.
